UNITED STATES PATENT OFFICE

2,529,916

COMBINED IGNITION AND STARTER SWITCH

Patrick H. Childress, Waynesboro, Va., assignor of
one-fourth to Dennis W. May, Waynesboro, Va.

Application October 12, 1948, Serial No. 54,147

7 Claims. (Cl. 200—44)

1

This invention relates to a switch and more particularly to a switch which is intended for use upon automobiles and other motor driven vehicles, it being one object of the invention to provide a starter switch which is associated with an ignition switch of the type covered by my prior Patent 2,443,977, the two switches being enclosed in a single housing and operated by a single key.

Another object of the invention is to provide a switch of such construction that when the key is inserted the ignition circuit will be closed, the starter circuit being closed by turning the key, and the circuit for the ignition being shut off by withdrawal of the key. It will thus be seen that since it is necessary to withdraw the key in order to halt operation of the motor, the driver of an automobile cannot forget to remove the ignition key. It will also be seen that after shutting off the motor an unauthorized person cannot operate the automobile. It will also be noted that since it is necessary to insert the ignition key and then turn it in order to close the starter circuit it will be impossible for a person to wear out the battery by merely pressing upon a starter switch button.

Another object of the invention is to provide a switch which may be mounted against the inner face of an instrument board or panel where it will be hidden from view, access to the switch being had through a key hole formed through the instrument board so that a key may be inserted into the switch when the automobile is to be operated.

Another object of the invention is to provide a switch wherein independently operated movable contact members are mounted in a switch box in such position that the movable contact member for the ignition circuit will be immediately closed when a key is fitted into the switch box and held closed until the key is removed, the movable contact for the starter circuit being yieldably held open and temporarily closed only during the time the key is turned and manually held in a position for closing it.

Another object of the invention is to provide a switch having a box or housing of such construction that its cover may be securely held upon the box and tampering with the switch mechanism therein thus prevented.

Another object of the invention is to provide a switch which is simple in construction, efficient in operation, and capable of being manufactured at low cost.

2

The invention is illustrated in the accompanying drawings wherein:

Fig. 1 is a perspective view showing the improved switch mounted in position for use.

Fig. 2 is a view showing the switch mechanism within the switch box in its initial state with the movable contacts in an opened position.

Fig. 3 is a view similar to Figure 2 showing the movable contact for the ignition circuit moved to a closed position.

Fig. 4 is a view similar to Figures 2 and 3 showing the movable contact for the starter circuit in a closed position.

Fig. 5 is a view similar to Figure 2 with portions in section and showing the manner in which a spring yieldably holds the movable contact of the ignition circuit in its opened position.

Fig. 6 is a sectional view taken vertically through the switch box along the line 6—6 of Figure 1.

Fig. 7 is a sectional view upon an enlarged scale taken longitudinally through the movable contact for the ignition circuit taken along the line 7—7 of Figure 5.

Fig. 8 is a fragmentary sectional view upon an enlarged scale taken along the line 8—8 of Figure 2.

Fig. 9 is a view upon an enlarged scale showing the movable contact of the starter circuit in elevation.

Fig. 10 is a fragmentary view showing the movable contact of the starter circuit in longitudinal section and mounted in position for use.

Fig. 11 is a view looking at one end of the bracket by means of which the movable contact of the starter circuit is slidably mounted.

Fig. 12 is a perspective view of the barrel for the key.

Fig. 13 is a perspective view of the member turned by the key for shifting the movable contact of the starter circuit to a closed position.

Fig. 14 is a view looking at the inner end of the member shown in Figure 13.

Fig. 15 is a perspective view of the key.

This improved switch has a box or housing 1 which may be formed of sheet metal, or other suitable material, and has a cover 2 which fits snugly about the box and has laterally projecting ears 3 formed with openings to receive fasteners 4 by means of which the switch box is held in place against the inner face of the instrument board 5 of an automobile. It will be understood that while the switch box has been shown mounted against the instrument board or panel it may be attached to the automobile at

any place within easy reach of the driver. Bolts 6 which are passed through openings formed in the annular wall 7 of the cover and engaged in nuts 8 or equivalent bosses carried by the annular wall 9 of the box serve to temporarily hold the cover and the box in engagement with each other and allow separation thereof so that wires may be connected with contacts within the box. After the wires have been connected with the contacts and the cover applied to the box the cover may be welded or soldered to the box, as shown at 10, and thus very effectively prevent tampering with the contacts or portions of the wires within the box after the box has been mounted against the inner face of the instrument panel. A neck or tube 11 project from the upper portion of the box to receive the flexible conduit 12 through which the wires 13, 14, and 15 pass and the cover is formed with an opening 16 to register with a keyhole opening 17 formed through the instrument board 5. The flexible conduit 12 is soldered or otherwise firmly secured to the box or housing and is passed through an opening 18 in the panel 19 of the automobile and its portion between this panel and the instrument board is thrust upwardly and secured by suitable clamps 20.

Within the box or housing is a stationary contact or bus bar 21 formed from a strip of conductive metal and having its opposite ends secured to blocks or insulation 22 by screws 23 which are passed through the strip and engaged in internally threaded sleeves 24 embedded in the blocks. Similar internally threaded sleeves 25 are embedded in the blocks in spaced and aligned relation to the sleeves 24 to receive screws 26 by means of which the blocks are secured upon the bottom of the box 1. This is clearly shown in Figure 8 and referring to this figure it will be seen that the stationary contact will be firmly supported and held in insulated relation to the box. The wire 13 is soldered or otherwise firmly secured to the stationary contact. A portion of the strip forming the stationary contact is cut longitudinally near one end and the cut portion downwardly bent and then laterally away from the strip to form a finger 27 extending from an ear 28.

The movable contact 29 for the ignition circuit consists of a strip of conductive metal 30 which has one end portion embedded in a block 31 formed of insulation. This block is pivotally mounted by a pin 32 which passes through a sleeve 33 mounted through the block and at its inner end the block carries a tongue or arm 34 which is pressed towards a position for abutting engagement with a stem 35 by a leaf spring 36 carried by a post 37. The metal strip 30 is bent back upon itself and secured by a screw 38 to form a clamp 39 through which a screw 40 passes and since the screw 40 is threaded through the clamp and extends transversely of the strip 30 it may be adjusted transversely of the movable contact and caused to project from a side of the contact towards the free end of the finger 27 for engagement therewith to close the ignition circuit when the movable contact is swung about the pivot pin 32 to a closed position. The spring 36 normally holds the movable contact in the opened position shown in Figures 2 and 5 but permits it to be swung to the closed position shown in Figure 3.

The circuit for the starter is normally open and is closed by means of a movable contact 41. This contact is shown in Figures 9 and 10, and refer-

ring to these figures it will be seen that it has a plunger 42 which is formed of insulating material. The plunger is slideable longitudinally through the openings 43 formed in the ears 44 of a bearing bracket 45. This bracket is mounted against the bottom of the box or casing 1 at right angles to the stationary contact 21 and is secured by a screw 45a which is passed through the bottom of the box and engages through a threaded opening formed in the base of the bracket. Since the side edge of the base of the bracket bears against a base 45b on the bottom of the box only a single screw is necessary to immovably secure the bracket in place. When the plunger is slid upwardly a metal contact pin 46 which is embedded in the plunger longitudinally thereof and projects upwardly therefrom will engage the ear 28 and close the circuit for the starter motor by way of the wires 13 and 14. A spring 47 is coiled about the plunger with its upper end bearing against the upper ear 44 of the bearing bracket and its lower end bearing against pins 48, and this spring yieldably holds the plunger in its lowered position to normally maintain this contact in an opened position. Metal wear rings or bands 49 which surround the plunger protect it from wear as it moves longitudinally through the bearing bracket and at its lower end the plunger carries a metal wear disk 50 which prevents excessive wear upon the lower end of the plunger.

The two movable contacts 29 and 41 are moved to a closed position by means of a single key 51. This key, which is shown in Figure 15, has a hollow or tubular barrel or stem 52 from which extends a radially projecting web 53. At the outer or rear end of the stem is a turning head 54. When the key is in use it is thrust inwardly through the registering openings of the instrument board 5 and the cover 2 of the switch box and as the key is pushed inwardly the stem 35 enters the barrel through the open outer end thereof and the key is thus mounted for turning movement about the stem. The front end of the key is cut diagonally to form a cam surface 55 and when the key is thrust into place about the stem the cam surface engages the edge face of the arm 34 confronting the stem and causes the movable contact 29 to be tilted about its pivot 32 and move the contact screw 40 into engagement with the finger 27 to close the ignition circuit. This circuit remains closed until the key is withdrawn and the spring 36 returns the contact to the opened position. Since it is necessary to withdraw the key from the switch box in order to open the ignition circuit the driver can not forget to remove the key and leave the automobile standing at a curb with the key in place and thereby allow a thief to enter the car and drive it away. The web 53 of the key fits into a wide slot or space 56 between the arms or legs 57 of a split ring 58 which surrounds the outer end of the stem 35 and since the key must be inserted with its web disposed in this slot the cam surface 55 will always be in position to move the movable contact 29 to the closed position. This space or slot also accommodates an arm 59 extending from a disk 60 which fits flat against the ring 58 and is turnably held in place by tongues 61 extending from the disk and bent across the marginal edge face of the ring and then back of the ring. The arm 59 is channel shaped or U-shaped in cross section to form a longitudinally extending recess 62 therein and the disk 60 is formed with a slot 63 which registers with this recess so that when the key is inserted its web

53 may enter the recess and cause the disk 60 and its arm 59 to be moved when the key is turned. A tongue 64 projects from the arm 59 for engaging the lower end of the slideable plunger 42 and when the key is turned after being inserted to effect closing of the ignition circuit the tongue 64 will force the plunger upwardly and move its contact pin 46 into engagement with the ear 28 from which the finger 27 projects. This will close the circuit for the starter motor which will be held closed as long as the key is held in the turned position. As soon as the engine is in operation the key is released and the spring 47 forces the plunger downwardly. The starter circuit will thus be opened and the key returned to its initial position but the ignition circuit will remain closed until the key is withdrawn from the switch box. It will thus be seen that the key is used for effecting closing the starter circuit as well as the ignition circuit and a separate switch operated by a push button or the like is not necessary for the starter circuit and wear upon the starter motor and drain of current from a battery by a person thoughtlessly or intentionally pressing upon the button of a starter switch will be eliminated. Having thus described the invention, what is claimed is:

1. A combined ignition and starter switch comprising a housing, a stationary contact in said housing, a movable contact for an ignition circuit and a movable contact for a starter circuit in said housing normally in an opened position, the movable contact for the ignition circuit being tilttable from a normally opened position into engagement with the stationary contact for closing the ignition circuit, the movable contact for the starter circuit being slideable from a normally opened position into engagement with the stationary contact for closing the starter circuit, a key adapted to be thrust longitudinally into the housing and being formed with a longitudinally extending cam surface for engaging the movable contact of the ignition circuit and tilting the same to its closed position when the key is thrust into the housing, said key being rotatable while in the housing, and a member actuated by rotation of the key for sliding the movable contact of the starter circuit to a closed position while the movable contact of the ignition circuit is still held closed by the key.

2. A combined ignition and starter switch comprising a housing, a stationary contact in said housing, a movable contact for an ignition circuit and a movable contact for a starter circuit in said housing normally in an opened position, the movable contact for the ignition being tilttable from a normally opened position into engagement with the stationary contact for closing the ignition circuit, the movable contact for the starter circuit being slideable from a normally opened position into engagement with the stationary contact for closing the starter circuit, a stem in said housing between the said movable contacts, a key adapted to be thrust longitudinally into the housing and fitted about the stem, said key having its inner end formed with a bevelled surface constituting a cam for engaging the movable contact of the ignition circuit and tilting the same to its closed position when the key is thrust into the housing, and a member adapted to be actuated by turning of the key to shift the contact for the starter circuit to its closed position while the key holds the ignition circuit closed.

3. A combined ignition and starter switch comprising a housing, a stationary contact in said

housing, a movable contact for an ignition circuit and a movable contact for a starter circuit in said housing, normally in an opened position, the movable contact for the ignition circuit being tilttable from a normally opened position into engagement with the stationary contact for closing the ignition circuit, the movable contact for the starter circuit being slideable from a normally opened position into engagement with the stationary contact for closing the starter circuit, a stem in said housing between the said movable contacts, a key adapted to be thrust longitudinally into the housing and fitted about the stem, said key having its inner end formed with a longitudinally extending bevelled surface constituting a cam for engaging the movable contact of the ignition circuit and tilting the same to its closed position when the key is thrust into the housing, a block about said stem through which the key passes when thrust into the housing, said block being formed with a radial slot and having arms at opposite sides of its slot secured to the housing, a disk rotatably carried by said block and formed with a slot and with a finger extending longitudinally between the arms of the block to limit turning of the disk, said key having a rib engaging the finger to move the finger transversely when the key is turned, and a tongue extending from the finger and engaging the movable contact of the starter circuit for shifting the same into engagement with the stationary contact to close the starter circuit when the key is turned while holding the ignition circuit closed.

4. A combined ignition and starter switch comprising a housing, a stationary contact in said housing, a movable contact for an ignition circuit and a movable contact for a starter circuit in said housing, the ignition contact consisting of a block of insulation pivotally mounted for tilting movement, a strip of conductive metal extending from one end of said block and bent back upon itself and secured to form a clamp, a terminal screw threaded through the clamp transversely of the strip and projecting from one side thereof a predetermined distance, an arm extending from the other end of the block, a spring engaging said arm and urging the said movable contact to a tilted position normally holding the terminal screw out of engagement with the stationary contact, a post in said housing engaged by a side face of said arm to limit tilting movement of the said movable contact away from the stationary contact to an opened position, a key adapted to be thrust longitudinally into said housing about said post and being provided with a cam surface for engaging the arm and tilting the movable contact of the ignition circuit into engagement with the stationary contact when the key is thrust inwardly, the spring serving to return the movable ignition contact to its opened position when the key is withdrawn from the housing, and a member engaged by the key and actuated by turning of the key to shift the movable contact of the starter circuit into engagement with the stationary contact when the key is turned in one direction.

5. A combined ignition and starter switch comprising a housing, a stationary contact in said housing, a movable contact for an ignition circuit and a movable contact for a starter circuit in said housing, the ignition contact consisting of a block of insulation pivotally mounted for tilting movement, a conductive member extending upwardly from one end of said block and adapted to have a circuit wire secured thereto, said con-

ductive member having engagement with the stationary contact when the said movable contact is tilted out of its normally opened position to a closed position, an arm extending downwardly from the other end of said block, a post in said housing engaged by said arm to limit movement of the movable contact towards an opened position, a key adapted to be thrust into the housing about the post and rotated about the post, said key having a longitudinally extending cam surface for engaging said arm and tilting the said movable contact to its closed position when the key is thrust inwardly into the housing and a member in said casing engaged by the key and movable by turning of the key into position to move the movable contact of the starter circuit into engagement with the stationary circuit to close the starter circuit while the key holds the ignition circuit closed.

6. A combined ignition and starter switch comprising a housing, a stationary contact in said housing, a movable contact for an ignition circuit and a movable contact for a starter circuit in said housing, the starter contact consisting of a bracket, a plunger of insulation slidable longitudinally through said bracket towards and away from the stationary contact, a terminal pin extending longitudinally from one end of said plunger towards the stationary contact, a spring urging the plunger longitudinally away from the stationary contact and normally holding the said movable contact open with the terminal pin out of engagement with the stationary contact, a key adapted to be thrust longitudinally into said housing and rotated therein, said key having a cam surface for engaging the movable contact of the ignition circuit and moving the same to its closed position when the key is thrust into the housing, and a member in the housing engaging the plunger and moved by the key to shift the plunger towards the stationary contact and close the starter circuit when the key is turned in one direction.

7. A combined ignition and starter switch comprising a housing, a stationary contact in said housing, a movable contact for an ignition circuit and a movable contact for a starter circuit in said housing, the starter contact consisting of

a bracket, secured to the housing, a plunger of insulation slidable longitudinally through said bracket towards and away from the stationary contact, a terminal pin extending longitudinally from one end of said plunger towards the stationary contact, a spring urging the plunger longitudinally away from the stationary contact and normally holding the said movable contact open with the terminal pin out of engagement with the stationary contact, a post in said housing, a block about said post formed with a radial slot and having arms at opposite sides of its slot secured to the casing, a key adapted to be thrust longitudinally into the housing and fitted about the post, said key having a longitudinally extending cam surface for engaging the movable contact for the ignition circuit and moving the same into engagement with the stationary contact when the key is thrust longitudinally into the housing, the last mentioned movable contact returning to an opened position when the key is withdrawn, a rib along the key disposed between the arms and limiting turning of the key, a disk rotatably mounted against said block and provided with a channeled strip disposed between the arms and carrying a laterally extending tongue engaging the plunger, said key being engaged in the channeled strip and serving to turn the disk and move the said strip and its tongue transversely to shift the plunger longitudinally and hold its terminal pin in engagement with the stationary contact to close the starter circuit when the key is turned in one direction while holding the ignition circuit closed.
